UNDERWEAR GARMENT

Louis Arons, Chicago, Ill., assignor to
Norman H. Arons, Chicago, Ill.

Application March 25, 1935, Serial No. 12,816

2 Claims. (Cl. 2—78)

Among the objects of my invention are to provide an underwear garment in one piece which employs a form-fitting short having a closable opening and a cutaway top integral with said short; to provide a combination top and short underwear garment in which the short acts as a supporter for a masculine wearer; to supply a top and short underwear garment wherein the top has an abbreviated and cutaway front and back portion so as to give greater comfort and freedom to a wearer; to create a combination top and short underwear garment wherein the short is form-fitting and yet has a portion thereof which may be opened or closed by means of a zipper, button or the like, and such other objects, advantages and capabilities as will later more fully appear and which are inherently possessed by my invention.

While I have shown in the accompanying drawing a preferred form of my invention yet I wish it understood that the same is susceptible of modification and change without departing from the spirit of my invention.

Referring more particularly to the drawing, Fig. 1 is an elevational view of my invention shown on a form; Fig. 2 is a perspective view of my invention shown in closed position; Fig. 3 is a perspective view of my invention with flap shown partially open; and Fig. 4 is a modified form of my invention shown with button means of closing flap.

The embodiment selected to illustrate my invention comprises a short 10 cut to be form-fitting to the body and legs of a wearer. The short 10 has cutout portions 11 and 12 through which are passed the legs of a wearer. The front portion 13 is connected to the back portion 14 at the crotch 15 by a connecting portion 16 which acts as a supporter for a masculine wearer. Integral with short 10 is top 17 having front portion 18 and back portion 19 which are preferably identical. My top portion 17 begins at the belt 20 or top portion of the short 10 and the lines of my top from both sides of the hips of the wearer move inward and upward until they almost meet at the abbreviated top 21 which just about reaches the chest and middle back of the wearer. Connecting the top portions 21 are a pair of shoulder straps 22 and 23 which pass over either shoulder of a wearer.

My short 10 has a slit 24, preferably located on the right side of said short, which slit may be opened or closed by the action of a zipper 25.

As a variation of my preferred embodiment the slit 24 may be closed by a plurality of buttons or the like, 26.

In use my underwear garment is form-fitting and allows great freedom by the elimination of the unnecessary part of the top to a wearer. In addition my combination saves the necessity of a separate top and short and the need of a separate supporter. The slit in my short, which may be instantaneously opened or closed, readily gives freedom to the wearer where the exposure of certain parts is necessary.

Having thus described my invention, I claim:

1. A combination unitary undergarment and supporter for men comprising a form fitting short having a pair of leg receiving portions connected by a permanently closed crotch portion, said crotch portion adapted to act as a supporter for a masculine wearer, said short having an opening and a fastening means for closing and exposing said opening, a belt integrally surrounding the top portion of said short, and a top integrally attached to the top of said belt, said top having identically shaped front and back portions, said portions of said top both curving upwardly and inwardly from both sides at the belt until they approximately meet at the middle chest and middle back of a wearer, so as to expose substantially all of the sides and the upper portions of the chest and back of a wearer, and a long pair of shoulder straps attached to and connecting the highest point of each of the back and front portions of said top.

2. A combination unitary undergarment and supporter for men comprising a form fitting short having a pair of leg receiving portions connected by a crotch portion, said crotch portion adapted to act as a supporter for a masculine wearer, said short having an opening and a fastening means for closing and exposing said opening, and a top integrally attached to the top of said short, said top having identically shaped front and back portions, said portions of said top both curving upwardly and inwardly from both sides from the bottom thereof until they approximately meet at the middle chest and middle back of the wearer, so as to expose substantially all of the sides and the upper portions of the chest and back of a wearer, and a long pair of shoulder straps attached to and connecting the highest point of each of the back and front portions of said top.

LOUIS ARONS.
